(57) **CLAIM**

The ornamental design for a razor handle, as shown and
described.

DESCRIPTION

FIG. 1 is a front perspective view of a razor handle, showing
our new design;

FIG. 2 is a front view of the razor handle illustrated in FIG.
1;

FIG. 3 is a rear view of the razor handle illustrated in FIG.
1;

FIG. 4 is a left side view of the razor handle illustrated in
FIG. 1;

FIG. 5 is a right side view of the razor handle illustrated in
FIG. 1;

FIG. 6 is a top view of the razor handle illustrated in FIG.
1;

FIG. 7 is a bottom view of the razor handle illustrated in
FIG. 1; and,

FIG. 8 is a front perspective view of the razor handle
illustrated in FIG. 1, shown in an environment of use.

The broken lines illustrate portions of the razor handle
forming no part of the claimed design. In FIG. 8, the
additional broken line showing of a razor head illustrates
environmental subject matter and forms no part of the
claimed design.

1 Claim, 8 Drawing Sheets
